FIRING MECHANISM

Emil Garrett, United States Marine Corps

Application April 22, 1944, Serial No. 532,236

9 Claims. (Cl. 42—1)

(Granted under the act of March 3, 1883, as
amended April 30, 1928; 370 O. G. 757)

1

This invention relates to firing mechanisms for weapons and has particular reference to a combined firing and recoil absorbing mechanism of novel construction which is particularly adapted for use in muzzle loading shoulder weapons. It is to be understood, however, that the new mechanism may be used in other types of weapons as well.

An object of this invention is to provide a combined firing mechanism and recoil absorbing mechanism particularly adapted to a muzzle loading shoulder weapon for firing relatively large caliber ammunition.

Another object of the invention is to provide a shoulder-fired long-range antitank or antipersonnel gun having spring means for decreasing the amount of recoil force transmitted to the shoulder of the user.

Another object of this invention is to provide a weapon as described above which utilizes a standard mortar barrel and ammunition.

A further object of this invention is to provide a device as referred to above which is light in weight, easy to assemble and disassemble, positive in operation, and simple to manufacture and to maintain in correct adjustment.

These and other objects of the invention will be obvious from the following specification and the accompanying drawings, in which

Fig. 1 is a longitudinal sectional view of a shoulder weapon embodying the invention, showing the mechanism in cocked condition ready for firing;

Fig. 2 is a view similar to Fig. 1 but showing the mechanism at the moment of firing before recoil commences;

Fig. 3 is a view similar to Fig. 1 but showing the mechanism at the end of the recoil movement before the beginning of counterrecoil with the piston turned 45° from the section shown in Fig. 1, and

Figs. 4, 5, 6 and 7 are cross-sectional views taken on lines 4—4, 5—5, 6—6 and 7—7, respectively, of Fig. 1.

In the drawings, a gun barrel housing or other such ammunition containing means 10 is threaded at its rear end to receive a closure 11 which has a rearwardly extending axial hub 12 and an axial passage 13 which is narrowed at its forward end to form a shoulder 14. The forward edge of the threaded portion of the closure forms a shoulder 27, the function of which will be explained presently. The closure has a forwardly extending thickened portion 15 against which a projectile is adapted to rest when the gun is loaded. A percussion firing pin 17 having an enlarged base 18

and a narrow forward portion 19 is mounted in the axial passage 13 in the cap and is normally maintained out of engagement with the base of the projectile by means of a spring 20 which surrounds the firing pin. Shoulder 17a on the pin contacts shoulder 14 to define the limit of forward movement of the firing pin, the firing pin being retained in the cap by suitable detent means (not shown). A firing pin housing 21 is threaded onto the hub 12 and encloses the spring 20.

The outer surface of the barrel is smooth and is mounted for longitudinal movement in a slide 22 to the rear end of which is threaded one end of a cylinder 23 which is closed and substantially sealed at its other end by a plug 24 carrying a butt plate 25. A shoulder 26 is provided at the rear end of the slide 22 in order to engage the shoulder 27 on the cap 11 for a purpose which will be described presently.

Slidably mounted in the cylinder 23 is a piston 28 provided with an axial boss 29 extending forwardly in axial alignment with the enlarged head 18 of firing pin 17 forming a striker therefor. The piston 28 has a rearwardly extending hollow cylindrical portion 30 having an outer diameter somewhat smaller than the inner diameter of the cylinder 23. A piston washer 31 and packing 32 surround the cylindrical portion 30 and are maintained in place thereon by a washer nut 33 which is threaded to the rear end of the hollow cylindrical portion 30 and is of approximately the same outer diameter as the piston 28, thus forming a rear bearing surface for the piston assembly. The use of the packing 32 results in a substantially airtight fit of the piston in the cylinder. That is, while substantially airtight, the fit of the piston in the cylinder permits a slow rate of air leakage around the piston into the rear end of the cylinder 23 after the weapon is fired, thus retarding return of the piston to the position shown in Fig. 1 as will be discussed presently.

The piston head 28 is provided with a plurality of openings 34, as shown in Figs. 3, 5 and 6. An annular valve washer 35 is mounted on the boss 29 and extends outwardly in a radial direction so as to cover the openings 34 in the piston head. A plurality of valve washer guides 36 are mounted in the piston head 28 and extend forwardly therefrom through openings in the valve washer 35. A coil spring 37 surrounds each of the guides 36, bearing against the enlarged head of the guide 36 and against the valve washer 35 so as to bias the valve washer towards engagement with the front surface of the piston head 28 to close openings 34.

A short, heavy buffer spring 38 is mounted in the rear end of the cylinder 23 on the plug 24 for cushioning the recoil of the weapon, as will be explained presently. A smaller coiled spring 39, called the recoil spring, bears at one end against the plug 24 and at the other end extends through the washer nut 33 and bears against the rear surface of the piston head 28 so as to urge the piston head forwardly. A coiled separator spring 40 is tightly mounted around the firing pin housing 21 at its forward end so as to bear against the base of closure 11. The rear end of spring 40 bears against the valve washer 35, tending to separate piston 28 from the base of the barrel.

A pair of spaced L-shaped guides 41 is attached to the lower side of the cylinder 23 so as to form a slideway closed at the front end by stop 42 attached to the underside of the cylinder and open at its rear end. A trigger group housing 42a comprising a hand grip 43 and trigger guard 44 is mounted by means of outwardly extending sliding lugs 45a in the slideway formed by guides 41. The trigger group housing is adapted to slide into place in members 41 from the open rear end of the housing 42a abuts stop 42, at which point the spring-pressed pivoted pawl 45 mounted on the rear end of the trigger group housing latches into a notch 46 on the lower side of the cylinder 23, latching the housing in place.

The trigger group comprises a mechanism for moving a sear 47 out of the path of the piston 28, the sear being pivotally mounted in the trigger group housing and being biased upwardly by a spring 48 toward its retaining position in which it is shown in Fig. 1. The underside of the rear end of the sear forms a hook-shaped tongue 49 which is adapted to be engaged by a similarly shaped upper end of disconnector 50 which is pivoted at its lower end to a forwardly extending arm 51 mounted on the pivoted trigger 52. A spring (not shown) is provided for urging the upper end of disconnector 50 forwardly into engagement with sear 47, and a spring 53 is attached at one end to a projection 54 extending inwardly from the trigger group housing, and at the other end to a rearwardly extending tongue 55 on the disconnector 50 so as to bias disconnector 50 upwardly to the position in which it is shown in Fig. 1, pulling upwardly on the lower end of the disconnector. A disconnector set screw 56 is threaded into the trigger group housing above the trigger guard so as to define a limit of downward movement of the disconnector 50 and to disengage the sear from the disconnector by a camming action on a forwardly extending shoulder 57 on the disconnector when the trigger has been moved far enough to move the sear out of the path of the piston 28. In order to provide a safety for the gun, a lever 58 mounted on the outside of the trigger housing is connected to a rotatable rod 59 which extends through the trigger group housing just under the sear 47. The rod 59 has a flat side and is mounted so as to obstruct downward movement of the sear except when the flat side of the rod is rotated upwardly adjacent to the bottom surface of the sear.

In operation, the gun uses ammunition of the trench mortar type in which the propellant explosive is contained in the base of the projectile, no cartridge case being used. The gun is manually cocked for the first shot by pressing the barrel inwardly in the cylinder 23 until the piston 28 is moved rearwardly from its uncocked position shown in Fig. 2 to the cocked position shown in

Fig. 1 in which the piston is held by sear 47 against the pressure of spring 39. The pressure on the barrel is then released, whereupon the barrel is moved forwardly into battery by the action of the spring 40. Forward movement of the barrel ceases when the forward shoulder 27 on the closure 11 contacts the shoulder 26 on slide 22. A projectile diagrammatically shown at 16 is slid into the muzzle until it rests against the cap 11 with its detonator adjacent to the opening 13 in the cap through which firing pin 19 is forced as will be described presently.

With the gun cocked and loaded, the butt plate 25 is held against the shoulder of the gunner and the weapon is aimed at the target by suitable sighting means (not shown). In order to fire the gun, the safety 58 must be moved to the "fire" position in which the flat side of rod 59 faces the bottom surface of the sear. When trigger 52 is moved rearwardly, trigger arm 51 and disconnector 50 are moved downwardly against the resistance of springs 53 and 48. Downward movement of the disconnector 50 moves the rear end of the sear 47 downwardly so that it no longer retains piston 28 in the cocked position, thus allowing the piston 28 to be moved forwardly by spring 39 to fire the gun as will be described presently.

Disconnector 50 moves downwardly until the angular shoulder 57 on its forward edge strikes the end of set screw 56 at which time a camming action causes the disconnector to pivot rearwardly to the position shown in Fig. 2, separating the disconnector from the tongue 49 of the sear and allowing spring 48 to move the sear upwardly to its retaining position shown in Fig. 1. The piston 28 and packing 32, which obstruct upward movement of sear 47 in Fig. 2, are moved rearwardly by recoil of the gun barrel so that, as shown in Fig. 3, there is no obstruction to upward movement of the sear. The release of pressure on the trigger 52 allows spring 53 to return the disconnector and trigger to their original positions, the linkage being so pivoted that the disconnector moves forwardly and again becomes hooked with the tongue 49 of the sear. By this arrangement, no matter how long the trigger is held by the gunner, the sear always swings back into retaining position in time to catch and retain piston 28 in its cocked position when the piston moves forwardly upon counter recoil, as will be described presently. The spring 53 also assures that upon release of the trigger, the linkages become operatively interconnected so that movement of the trigger moves the sear to fire the gun.

When the sear 47 is moved downwardly by pressure on the trigger as described above, the piston 28 is freed from the detent action of the sear and is moved forwardly by spring 39 until it strikes the enlarged base 18 of the firing pin 17 and drives the same forwardly into firing engagement with the detonator on the rear of the projectile. When the projectile is fired from the gun, the recoil forces drive the barrel and the parts mounted on the rear end thereof rearwardly, the piston 28 and the parts mounted thereon moving with the barrel. The recoiling parts are opposed first by spring 39 and, upon further movement, by spring 38, as shown in Fig. 3. Compression of the air entrapped in the cylinder 23 behind the piston 28 causes the valve washer 35 to open against the pressure of springs 29, as shown in Fig. 3, permitting the air to escape into the forward end of the cylinder which is open to the atmosphere.

When the force of recoil has been absorbed by

springs 39 and 38, the piston and barrel are counterrecoiled by these same springs, the piston and barrel being moved forwardly toward their original positions. During this counterrecoil movement, the air within the cylinder 23 behind the piston is under reduced pressure, and springs 37 move valve washer 35 into contact with the forward surface of piston 28, substantially closing the openings 34 and causing a pneumatic buffing of the counterrecoil motion. The slow leakage of air around piston 28 into the rear end of cylinder 23 permits a slow return of the barrel to battery and prevents the barrel from being forced into battery too suddenly with the resulting deterioration of the mechanism and jolt to the gunner. The piston and barrel are moved forwardly in counterrecoil by springs 39 and 38 until the piston 28 strikes the sear 47, which has been returned to its original retaining position by spring 48 as described above. At this point, the piston 28 is halted in its forward movement while the barrel 10 is moved by spring 40 until it reaches the battery position described above. The gun is in cocked condition and is ready for reloading and firing. Manual cocking of the gun is necessary only before the firing of the first shot in case the piston is in its extreme forward position, the gun being automatically cocked after each shot as described above. With a gun made in accordance with my invention, a 60 mm. mortar projectile has been fired from a man's shoulder with comparatively slight recoil force against the shoulder. The weapon is light in weight and requires no cumbersome mount. A standard mortar barrel and projectile are utilized, thus reducing the number of different types of ammunition and barrels which must be procured. The gun is simple in construction and operation, being particularly adapted to large-scale production and to operation after very little instruction.

While the preferred form of the invention has been illustrated and described, it is to be understood that other variations and modifications may be made without departing from the scope of the invention as defined by the appended claims.

The invention herein described may be manufactured and used by or for the Government of the United States of America for governmental purposes without the payment of any royalties thereon or therefor.

I claim:

1. In a firearm having a slide and a barrel reciprocably mounted in said slide for receiving a projectile, the combination of a firing pin mounted in the rear end of the barrel, means for biasing the pin toward a nonfiring position, a striker biased toward firing engagement with said firing pin, said striker being movable independently of the barrel but being movable rearwardly by said barrel on recoil of the barrel, biasing means maintaining said striker and said barrel separated and retaining said barrel in battery when said striker is held in cocked position, a detent for locking said striker in cocked position separated from said pin, and means for moving said detent to an inoperative position to release the striker.

2. In a firearm having a slide and a barrel reciprocably mounted in said slide for receiving a projectile, the combination of firing means carried by the rear end of the barrel, a striker for operating said firing means, means for biasing said striker forwardly toward contact with said

firing means, detent means for maintaining said striker in cocked position and movable to release said striker for forward movement under the influence of said first named biasing means to fire the gun, and biasing means between said striker and said barrel for maintaining the barrel in battery position when the striker is held by the detent means, said last biasing means exerting a smaller force than the first biasing means.

3. In a muzzle loading firearm having a slide and a barrel reciprocably mounted in the slide for receiving a projectile, the combination of a cylinder closed at one end and attached at the other end to the slide to enclose the rear end of the barrel, a piston slidably mounted in the cylinder, firing means mounted on the rear end of the barrel and operable by said piston, resilient means mounted in said cylinder for biasing the piston toward firing engagement with said firing means and for resisting recoil movement of said piston and barrel, a movable detent normally retaining said piston in cocked position wherein said resilient means is under tension, resilient means mounted between said piston and the barrel for maintaining the barrel in firing position separated from the piston when the piston is in cocked position, said last resilient means being weaker than the first resilient means, and means for moving said detent to an inoperative position to fire the gun.

4. In a muzzle loading firearm having a slide and a barrel reciprocably mounted in the slide for receiving a projectile, the combination of a firing pin mounted in the rear end of the barrel, means for biasing the pin toward a nonfiring position, a striker biased toward firing engagement with said firing pin, said striker being movable independently of the barrel but being movable by said barrel on recoil of the barrel, a coiled spring mounted between said barrel and said striker for maintaining the barrel separated from the striker and for retaining said barrel in battery when said striker is held in cocked position, a detent for locking said striker in cocked position, and means for moving said detent to an inoperative position to release the striker.

5. In a muzzle loading firearm having a slide and a barrel reciprocably mounted in the slide for receiving a projectile, a cylinder closed at one end and attached at the other end to the slide to enclose the rear end of the barrel, a piston slidably mounted in the cylinder, said piston having a rearwardly extending tubular portion, packing surrounding said portion, a washer nut mounted on the rear end of said tubular portion for holding said packing in place, firing means mounted on the rear end of the barrel and operable by the piston, resilient means mounted in said cylinder for biasing the piston toward firing engagement with said firing means and for resisting recoil movement of said piston and barrel, a movable detent normally retaining said piston in cocked position wherein said resilient means is under tension, resilient means mounted between said piston and the barrel for maintaining the barrel in firing position separated from the piston when the piston is in cocked position, said last resilient means being weaker than the first resilient means, and means for moving said detent to an inoperative position to fire the gun.

6. In a muzzle loading firearm, a slide, a barrel reciprocably mounted in the slide for receiving a projectile, a cylinder closed at one end and at-

tached at the other end to the slide to enclose the rear end of the barrel, a packed piston slidably mounted in the cylinder with a substantially airtight fit, a longitudinal opening extending through said piston, spring-pressed means closing said opening and movable to uncover said opening on rearward movement of the piston, firing means mounted on the rear end of the barrel and operable by said piston, resilient means mounted in said cylinder for biasing the piston toward firing engagement with said firing means and for resisting recoil movement of said piston and barrel, a movable detent normally retaining said piston in cocked position wherein said resilient means is under tension, resilient means mounted between said piston and the barrel for maintaining the barrel in firing position separated from the piston when the piston is in cocked position, said last resilient means being weaker than the first resilient means, and means for moving said detent to an inoperative position to fire the gun.

7. In a muzzle loading firearm, a slide, a barrel reciprocably mounted in the slide for receiving a projectile, a cylinder closed at one end and attached at the other end to the slide to enclose the rear end of the barrel, a piston mounted in the cylinder, said piston having a hollow rear portion, firing means mounted on the rear end of the barrel and operable by said piston, a relatively strong coiled spring in said cylinder behind the piston, one end of the spring bearing against the closed rear end of the cylinder, the other end of the spring extending into the hollow rear portion of the piston so as to urge said piston forwardly toward firing engagement with said firing means and to resist recoil movement of said piston and barrel, a movable detent normally retaining said piston in cocked position wherein said resilient means is under tension, resilient means mounted between said piston and the barrel for maintaining the barrel in firing position separated from the piston when the piston is in cocked position, said last resilient means being weaker than the first resilient means, and means for moving said detent to an inoperative position to fire the gun.

8. A mortar comprising a tubular casing, mov-

able means within said casing for containing ammunition in a firing position, a closure at the end of said containing means juxtaposed to said ammunition, said closure having a spring biased percussion firing means therein, a spring driven striker for said firing means, and spring means mounted between said striker and said closure for maintaining said firing means in an impact receiving position with respect to said striker.

9. A mortar comprising a tubular casing, a housing movable within said casing for containing ammunition in a firing position, a closure at the end of said casing juxtaposed to said ammunition, said closure having a spring biased percussion firing means therein, a striker for said firing means, a coil spring for driving said striker within said casing from a first to a second position, releasable means maintaining said striker in said first position and spring means positioned between said striker and closure for maintaining said firing means displaced from said striker adjacent said second position.
